RACKET STRINGING DEVICE

Alan L. Becket, East Orange, N. J.

Application November 3, 1934, Serial No. 751,410

2 Claims. (Cl. 273—73)

This invention relates to a device for stringing rackets. It relates particularly to what is known as patching work. When one or more of the strings in a racket become worn or broken it is not necessary in most cases to restring the entire racket but merely to replace certain worn or broken strings with new strings. The worn or broken strings are cut out and removed from the racket. The new strings which take the place of the strings removed must be joined at both ends with the strings left in the racket. One end of the new string is looped with an end of the old string and the looped connection is pulled tightly into a racket frame hole. The connection is called a splice. The first splice is made with the new string before it is strung in the racket and thus the string may be gripped and is easy to manipulate. After the new string is strung in the racket its other end must then be spliced with the end of the other portion of the old string left in the racket. This splice is a difficult one to make and at the same time maintain a correct tension on the new string. Both new and old strings must be tight while making this final splice. It is the object of this invention to make it less difficult to effect this final connection between the strings in a patch.

In the drawing Fig. 1 is a side view of the device. Figs. 2, 3, 4, 5, and 6 are views of clamping members. Figs. 7, 8, 9, and 10 are views of modifications of the device.

In Fig. 1 the arm 1 is placed against the outside surface of a racket frame 2, the clamping jaws 3 grip the string 4 when pressure is exerted laterally by the internally threaded cap 5 upon the flanged sides of the jaws 3. The cap 5 is screwed upwardly so that the jaws 3 are squeezed against the string 4 to clamp the string securely. The position of the clamping means 3 and 5 may be adjusted on arm 1 by means of thumb screw 6. Before the string is clamped it is first pulled to the proper tension. A stringer's awl may be used to hold the string while the device is being applied. The final splice is made by pulling the looped strings into the string hole of the frame where they become securely locked. It is obvious that the string 4 must be held taut while the splice is being made. The common method of making a patch connection or splice is to hold the string 4 taut with a pair of pliers and at the same time pull thru the splice. This operation is difficult to manipulate. It results frequently in the last string of a patch being loose instead

of being as tight as the other strings. By using this invention the pliers are not needed and both hands of the stringer become free to make the splice. The device maintains the desired tension upon the last string of the patch. Fig. 2 is a jaw of the clamp member with corrugations at 7 and a centering recess at 8. Fig. 3 is the opposite clamping jaw with centering prominence at 9. Fig. 4 is a side view of a jaw showing the hole 10 and threads 11. Fig. 5 is a clamping member used to hold the jaws together as in a chuck. Fig. 6 is a cross section of one form of clamping means of threaded chuck construction. Fig. 7 is a side view of a modified form of the device in which the clamping means is a set screw 12. Fig. 8 is a perspective view of same showing the opening at 16 which permits an awl to be introduced for the purpose of holding the string while the device is applied. Fig. 9 is a side view of the device showing the set screw 11 carrying a corrugated swivel cap 13 and a double adjusting set screw 14. Fig. 10 is a downward view of Fig. 9 with set screw 12 omitted, the set screws 14 make it possible to adjust the device against the curved outside surface of a racket frame.

I claim:

1. A racket repairing device of the character described consisting of a main body portion, string clamp, frame brace and tightening means, the said string clamp being located at one end of said main body and the said frame brace being located at the opposite end of said main body, the said tightening means being located upon the said body portion and being a part thereof consisting of a screw means for drawing a racket string tight when the said string clamp grips a racket string and the said frame brace engages the outside surface of a racket frame under pressure exerted by the said tightening means.

2. A racket stringing device consisting of a string clamp, brace member, body member and tightening means, the said string clamp being located at one end of the body member and the said brace member being located at one end of the body member, the tightening means being located upon the said body member between the said string clamp and the said brace member, the said tightening means providing screw means for drawing a string toward the portion of a racket frame upon which the said frame brace is positioned.

ALAN L. BECKET.
